STENCIL PRINTING MACHINE

Hugo H. Stoelting, Cleveland, Ohio

Application October 10, 1932, Serial No. 637,054

19 Claims. (Cl. 101—125)

This invention relates to stencil printing machines and particularly to a rocking-motion or cradle-type machine with mechanism to control the position and alignment of the stencil reproductions on multiple copies.

The principal object of my invention is to provide means for the commercial production of a light and comparatively inexpensive stencil printing machine, which may be carried like a portable typewriter, simple and easy to operate, with provision for fixing the position and alignment of the stencil reproductions on successive copies. A further object is to devise means for attaching an ink pad in said stencil printing machine. Another object is to devise means for attaching a stencil in said machine. Still another object is to devise means for guiding and aligning paper in said machine.

The foregoing and other objects are obtained by the devices illustrated in the accompanying drawings and described below. It is to be understood that the device is not limited to the specific form thereof disclosed herein.

Of the accompanying drawings:

Figure 1 is a schematic side elevation of a stencil printing machine embodying the invention;

Figure 2 is a diagrammatic side elevation of the machine illustrating the path of movement of the various parts thereof;

Figures 3^A, 3^B, 3^C and 3^D are detail sections of a portion of the machine illustrating the method of attaching the ink pad and stencil;

Figure 4 is a perspective detail of a paper guide used in the machine;

Figure 5 is a side elevation of a modified form of the machine;

Figure 6 is a side elevation of the machine illustrated in Figure 5, with the parts closed and a cover applied thereover;

Figure 7 is a side elevation, partly broken away, of the machine shown in Figure 5, illustrating the lid raised to permit ink or a stencil to be applied;

Figures 8 and 9 are perspective details of the forward and rear portions of the modified form of machine shown in Figure 5;

Figures 10 and 11 are perspective views of two further modified forms of the machine;

Figures 12 and 13 are perspective views, partly broken away, of further modified forms of machines embodying the invention.

Referring in detail to Figure 1 of the drawings, the numeral 15 denotes the base of the machine upon which are attached a pair of lugs 16.

Links 17 are pivoted at 18 at one end thereof to lugs 16 and a cover or top plate 19 is in turn pivoted at 20 at its rearward portion to the other ends of links 17. The forward portion of the top plate 19 has pivoted thereto at 21 a pair of rocker arms 22 formed with an arcuate stencil platen 23 between and beyond said arms. A pair of connecting bars 24 are pivoted at 25 to arms 22 and at 26 to links 17. Links 17, arms 22, bars 24 and top plate 19 are pivoted similar to 10 a parallel bar arrangement but as diagrammatically illustrated in Figure 2 do not move as a parallelogram. This is due to the fact that links 17 are pivoted at points 18 as centers on the base, whereas rocker arms 22 during the 15 printing operation are pivoted about a center 27 which is the center of arc of platen 23 and which is above the top plate, and which moves in a line parallel to the base.

Pivot points 20, 26, 21 and 25 take the path 20 shown in dotted lines in Figure 2 during the rocking movement of platen 23. Owing to the fact that the parts above mentioned do not move as a true parallelogram there is a tendency for slight relative motion between the platen 23 and the 25 base 15 toward the ends of the arc. Provision is made to avoid such relative movement by forming slots 28 in bars 24 at pivot points 26 to afford a slight lost motion between bars 24 and links 17. This slot to provide lost motion may be 30 placed at any of the other pivot points as will be later described. Hooks 29 on the extended ends of bars 24 may be engaged with a hook 30 attached to base 15 whereby platen 23 may be retained in a raised position while the machine is 35 not in operation.

The cover or top plate is provided with a knob or handle 31 by which the device may be operated to rock the platen to and fro during the printing operation.

The paper guide shown in detail in Figure 4 consists of a clamp 32 adapted to be tightened against base 15 by means of a nut 33 and a screw 34 passing through a slot 35 in base 15. An angular guide member 36 has one arm thereof slidably 45 engaged under clamp member 32. Since the paper guide parts are slidable fore and aft and laterally and may also be pivoted about screw 34, the paper 37 may be guided into any desired relative position with respect to platen 23.

Platen 23 is provided with a plurality of perforations 37' whereby ink applied to the back of the platen will penetrate therethrough and become absorbed in a felt or fabric pad 38 attached to the outer surface of platen 23 by means 55

of a fabric band 39. Band 39 is provided at its ends with fastening means 40 which extend across the width of band 39 and clamp same against a transverse wire 41 for securely fastening the end thereof. Fastening means 40 is provided with a hook formation 42 which when engaged with end flange 43 on platen 23 in the manner shown in Figure 3^A and moved in the direction of the arrow, will snap past a dead center and retain itself in position as shown in Figure 3^B.

The stencil 44 which may be of the usual type is applied about the ink pad in the manner shown in Figures 3^C and 3^D, the cardboard tab 45 on the end of the stencil being bent as shown and being clamped into place by a channel member 46 carried by a pair of spring-pressed lever arms 47 pivoted to rocker arms 22. The other end of the stencil may be clamped to the platen in like manner.

In the modified form of the invention shown in Figure 5 like parts of the machine bear the same reference numerals as those of Figure 1 with the exponent "a". In this form of the machine the slot 48 for affording lost motion is formed in the forward end of bars 24^a. Bars 24^a are connected at the rear of the machine by a bar 49 which may be engaged with hook 30^a to retain the platen in raised position as shown in Figures 5, 7 and 9. Lugs 18^a and hook 30^a may be made integral for attachment to base 15^a. The rear portion of the machine is braced against distortion by connecting links 17 across the bottom as shown in Figure 9 and by riveting or otherwise attaching thereto a reinforcing bar 50.

Top plate 19^a is detachably secured to links 51 attached to rocker arms 22^a, by means of spring-pressed detents 52 which may be engaged by knobs 53 to release the top plate when the platen is to be inked or the stencil is to be changed as shown in Figures 7 and 9. When the top plate 19^a is again to be connected to the rocker arms it is snapped into place over the detents 52, 52, the latter being guided into their seats 54 by means of guide flanges 55 which extend diagonally with respect to the top plate. This form of the machine is illustrated with a cover 56 which may be applied over the machine as illustrated in Figure 6 and retained in place by spring-pressed detents 57, 57. In order to remove the operating knob 31^a from its normal position and to lock the parts in fixed position when the cover is in place, knob 31^a is attached to a hinged plate 58 which may be swung around in the position shown in Figure 6 and engaged by the forward detent 57. The machine is thus very compact when not in use.

In the modified form of the machine shown in Figure 10 parts similar to the foregoing form of the invention are marked with the same numerals with the exponent "b". In place of the top plate there is substituted a U-shaped member comprising arms 59, 59 and a bar 60 connecting same across the rear of the machine. In this form of the device the slot 61 for affording lost motion is formed in bars 59 at the upper pivots 20^b. Links 17^b and their top portions are connected by a reinforcing bar 62. The operating knob 31^b is attached to a U-shaped member 63 which is affixed to the sides of platen 23^b. The latter may be provided with a cover plate 64 to guard against the ink being thrown from the interior of the platen.

In the modified form of the machine shown in Figure 11 the parts are similar to those of the form shown in Figure 10 and are similarly de-

noted by numerals with the exponent "c". In this form of the device the platen is made entirely detachable from the parallel bar mechanism and is secured thereto by means of screws 65 attached to member 63^c and engageable in slots 66 formed in yoke member 67 to which are connected parallel bars 59^c and 24^c.

In the form of the device shown in Figure 12 the device is similar to that of the forms shown in Figures 5 to 9 inclusive but has been modified as 10 to the manner of engaging the detent with the top plate. In this form of the device the ends of spring-pressed detents 52^d are engageable directly in apertures 68 in top plate 19^d. A modified form of means for clamping the stencil in position is also shown. This consists of pivot arms 47^d attached to the ends of channel members 46^d, springs 69 being attached to the front and rear lever arms 47^d for yieldingly clamping the channel members 46^d against the platen.

Figure 13 illustrates a modified form of pivoted connection for connecting the top plate 19^e to the base 15^e. This connection is made through a plate 70 respectively hinged at 71 and 72 to the top plate and to a plate 73 attached to base 25 15^e. A hook device 30^e is formed integral with plate 73 for engagement with hook 74 attached to the top plate for retaining the platen in raised position.

In the operation of the stencil printing machine the ink pad and band 39 are assembled with the platen as heretofore described and inked from the back side of the platen. The stencil is applied as above mentioned by creasing or folding the cardboard tab. The latter may be provided 35 with perforated line across the cardboard for determining the position of the crease. The crease thus serves as a guide for the proper alignment of the stencil after the tab has been clamped by channel member 46. One or more 40 sheets of paper may then be placed on the base against guide bar 36 and printed upon by bringing the platen into engagement with the paper at one end of the arcuate portion thereof and rocking the platen over the paper until the other end 45 of the platen is engaged with the paper. The platen is then raised, the top sheet of paper removed and the platen returned to its original position while raised, the lost motion being taken up on the same end of the stroke as each sheet 50 is printed. If desired, however, one sheet may be printed as the platen is rocked in one direction while the succeeding sheet is printed while the platen is rocked in the opposite direction. The parallel bar arrangement insures that the platen 55 will be retained in alignment and in the same relative position with respect to each printed sheet.

While a lost motion slot is illustrated at one of the pivot points of the parallel bar arrangement, this may be dispensed with where the arc of the platen subtends a relatively small angle.

In the use of the form of the invention illustrated in Figure 11 the platen may be entirely detached from the parallel bar mechanism and 65 used as a simple hand stenciling platen if desired.

The embodiment of the invention disclosed herein is to be taken in a descriptive and not a limiting sense, accordingly various modifications of the invention may be resorted to without departing from the spirit of the invention or the scope of the appended claims.

What is claimed is:

1. The combination with a base plate, of a curved platen, means for mounting an ink pad 75

- on the convex surface of said platen, means for mounting a stencil over the surface of said pad, means whereby said stencil may be brought into contact with a sheet of paper placed on said 5 base plate, so as to cause a print or reproduction of said stencil to be made on said paper as a rocking motion is imparted to the platen, and means comprising a parallel bar mechanism between said platen and said base plate whereby 10 positive duplication of position of successive stencil prints or reproductions on said copy paper may be made.
2. The combination with a platen, of means for mounting thereon a stencil having a cardboard tab attached thereto, said stencil being adapted to be formed with a transverse crease or fold extending at right angles to the side margins of the stencil, said means comprising a transverse spring-pressed channel member extending at 20 right angles to the side margin of said platen and adapted to engage said crease or fold in the tab on said stencil for clamping same to the end of said platen, whereby said stencil will be aligned with respect to said platen.
- 25 3. The combination with a base plate, of a stencil printing platen, a parallel bar mechanism connecting said platen to said base plate, and means on said base plate for retaining said mechanism and printing platen in an elevated position.
- 30 4. The combination with a base plate, of a rocking motion platen for stencil printing on a sheet of paper on said base plate, a parallel bar mechanism connecting said platen to said base plate, and means on said base plate for adjustably guiding the position of said paper with respect to said base plate for adjustment of the alignment of the stencil print on said paper.
- 40 5. The combination with a base plate, of a rocking motion platen for stencil printing on a sheet of paper on said base plate, a parallel bar motion control mechanism connecting said platen and said base plate, and means affording lost motion in said parallel-bar control mechanism to permit 45 free rolling motion of the stencil printing platen over said paper.
- 50 6. The combination with a base plate, of a rocking motion stencil printing platen, means comprising a parallel bar mechanism for linking said platen to said base plate whereby the position of the stencil print or reproduction produced by said printing platen will be fixed with respect to said base plate, and means for guiding a stack of paper on said base plate in a fixed position with 55 respect thereto so that successive sheets of said stack of paper will be identically aligned and positioned as each sheet of paper is printed and removed in turn.
- 60 7. The combination with a base plate, of a stencil printing platen, and a parallel bar mechanism connecting said platen to said base plate.
- 65 8. The combination with a base plate, of a stencil printing platen, means for mounting an ink pad and stencil on the convex surface of said platen, a parallel bar mechanism for linking said printing platen to said base plate.
- 70 9. A duplicating machine comprising a base, a pair of lugs affixed to said base, a pair of links having one end of each thereof pivoted to one of said lugs, a printing platen having an arcuate printing surface, said platen being mounted to move over said base with a rocking motion and adapted to have an ink pad and stencil attached thereto, a pair of arms formed on the sides of 75 said platen, a pair of bars pivotally connected to the ends of said arms and to the ends of said links remote from the ends thereof pivoted to said lugs, and a second pair of bars substantially parallel to said first-named pair of bars, said second-named pair of bars being pivotally connected at one end of each thereof to the arms on said platen intermediate the arcuate face and the end portions thereof, the other of each of the ends of said second-named pair of bars being pivotally connected to said links intermediate the end portions thereof, said links, said arms and said first and second-named pairs of bars comprising a parallel bar mechanism for controlling the rocking motion of said platen with respect to said base, a pivot point on each side of said parallel bar mechanism being formed with a slot affording lost motion as said platen is rocked about its arcuate surface, an extension formed on said second pair of bars, and a hook member affixed to said base for engagement with said extension for retaining the parallel bar mechanism and platen in a raised position.
10. A duplicating machine comprising a base, a pair of lugs affixed to said base, a pair of links having one end of each thereof pivoted to one of said lugs, a printing platen having a cylindrical arcuate printing surface, said platen being mounted to move over said base with a rocking motion and adapted to have an ink pad and stencil attached thereto, a pair of arms formed on the sides of said platen, a pair of bars pivotally connected to the ends of said arms and to the ends of said links remote from the ends thereof pivoted to said lugs, and a second pair of bars substantially parallel to said first-named pair of bars, said second-named pair of bars being pivotally connected at one end of each thereof to the arms on said platen intermediate the arcuate face and the end portions thereof pivoted to said first named bars, the other of each of the ends of said second named pair of bars being pivoted to said links intermediate the end portions thereof, said links, said arms and said first and second named pairs of bars comprising a parallel bar mechanism for controlling the rocking motion of said platen with respect to said base to assure identical alignment and positioning of the stencil impression during successive strokes of said platen, one of the corresponding members on each side of said parallel bar mechanism being formed at its pivot point with a slot affording lost motion in said parallel bar mechanism as said platen is rocked about its arcuate surface, means for locking said parallel bar mechanism and printing platen in fixed position when the machine is not in use, an extension formed on said second pair of bars, a hook member affixed to said base for engagement with said extension for retaining the parallel bar mechanism and platen in a raised position while ink is being applied to said platen or while a stencil is being attached thereto.
11. A duplicating machine comprising a base, a pair of lugs affixed to said base, a pair of links having one end of each thereof pivoted to one of said lugs, a platen having an arcuate printing surface, said platen being mounted to move over said base with a rocking motion and adapted to have a printing stencil attached thereto, a pair of arms formed on the sides of said platen, a pair of bars pivotally connected to the ends of said arms and to the ends of said links remote from the ends thereof pivoted to said lugs, and a second pair of bars substantially parallel to said first-named pair of bars, said second-named pair of bars being pivotally connected at one end of each

- thereof to the arms on said platen intermediate the end portions of said arms and the arcuate surface thereof, the other of each of the ends of said second-named pair of bars being pivoted to said links intermediate the end portions thereof, said links, said arms and said first and second-named pairs of bars comprising a parallel bar mechanism for controlling the rocking motion of said platen with respect to said base, a pivot point on each side of said parallel bar mechanism being formed with a slot affording lost motion as said platen is rocked about its arcuate surface, and means for retaining the parallel bar mechanism and platen in a raised position.
15. A duplicating machine comprising a base, a printing platen having an arcuate printing surface, said platen being mounted to move over said base with a rocking motion and adapted to have an ink pad and stencil attached thereto, means comprising a pivoted parallel bar mechanism for controlling the rocking motion of said platen with respect to said base, a pivot point on each side of said parallel bar mechanism being formed with a slot affording lost motion as said platen is rocked about its arcuate surface, and means for retaining the parallel bar mechanism and platen in a raised position.
20. 12. A duplicating machine comprising a base, a pair of lugs affixed to said base, a pair of links having one end of each thereof pivoted to one of said lugs, a platen having an arcuate printing surface, said platen being mounted to move over said base with a rocking motion and adapted to have a printing stencil attached thereto, a pair of arms formed on the sides of said platen, a pair of bars pivotally connected to the ends of said arms and to the ends of said links remote from the ends thereof pivoted to said lugs, and a second pair of bars substantially parallel to said first-named pair of bars, said second-named pair of bars being pivotally connected at one end of each thereof to the arms on said platen intermediate the end portions of said arms and the arcuate surface thereof, the other of each of the ends of said second-named pair of bars being pivoted to said links intermediate the end portions thereof, said links, said arms and said first and second-named pairs of bars comprising a parallel bar mechanism for controlling the rocking motion of said platen with respect to said base.
25. 13. A duplicating machine comprising a base, a pair of lugs affixed to said base, a pair of links having one end of each thereof pivoted to one of said lugs, a platen having an arcuate printing surface, said platen being mounted to move over said base with a rocking motion and adapted to have a printing stencil attached thereto, a pair of arms formed on the sides of said platen, a pair of bars pivotally connected to the ends of said arms and to the ends of said links remote from the ends thereof pivoted to said lugs, and a second pair of bars substantially parallel to said first-named pair of bars, said second-named pair of bars being pivotally connected at one end of each thereof to the arms on said platen intermediate the end portions of said arms and the arcuate surface thereof, the other of each of the ends of said second-named pair of bars being pivoted to said links intermediate the end portions thereof, said links, said arms and said first and second-named pairs of bars comprising a parallel bar mechanism for controlling the rocking motion of said platen with respect to said base.
30. 14. A duplicating machine comprising a base, a printing platen having an arcuate printing surface, said platen being mounted to move over said base with a rocking motion and adapted to have an ink pad and stencil attached thereto, and means comprising a pivoted parallel bar mechanism for controlling the rocking motion of said platen with respect to said base, a pivot point on each side of said parallel bar mechanism being formed with a slot affording lost motion as said platen is rocked about its arcuate surface.
35. 15. A duplicating machine comprising a base, a pair of lugs affixed to said base, a pair of links having one end of each thereof pivoted to one of said lugs, a platen having an arcuate printing surface, said platen being mounted to move over said base with a rocking motion and adapted to have an ink pad and stencil attached thereto, a pair of arms formed on the sides of said platen, a pair of bars pivotally connected to the ends of said arms and to the ends of said links remote from the ends thereof pivoted to said lugs, and a second pair of bars substantially parallel to said first-named pair of bars, said second-named pair of bars being pivotally connected at one end of each thereof to the arms on said platen intermediate the end portions of said arms and the arcuate surface thereof, the other of each of the ends of said second-named pair of bars being pivoted to said links intermediate the end portions thereof, said links, said arms and said first and second-named pairs of bars comprising a parallel bar mechanism for controlling the rocking motion of said platen with respect to said base.
40. 16. A duplicating machine comprising a base, a pair of lugs affixed to said base, a pair of links having one end of each thereof pivoted to one of said lugs, a platen having an arcuate printing surface, said platen being mounted to move over said base with a rocking motion and adapted to have an ink pad and stencil attached thereto, a pair of arms formed on the sides of said platen, a pair of bars pivotally connected to the ends of said arms and to the ends of said links remote from the ends thereof pivoted to said lugs, and a second pair of bars substantially parallel to said first-named pair of bars, said second-named pair of bars being pivotally connected at one end of each thereof to the arms on said platen intermediate the end portions of said arms and the arcuate surface thereof, the other of each of the ends of said second-named pair of bars being pivoted to said links intermediate the end portions thereof, said links, said arms and said first and second-named pairs of bars comprising a parallel bar mechanism for controlling the rocking motion of said platen with respect to said base.
45. 17. A duplicating machine comprising a base, a printing platen having an arcuate printing surface, said platen being mounted to move over said base with a rocking motion and adapted to have an ink pad and stencil attached thereto, and means comprising a parallel bar mechanism for controlling the rocking motion of said platen with respect to said base, said mechanism including a detachably secured cover plate.
50. 18. The combination with a curved platen formed with end portions, an ink pad of absorbent material mounted on the convex surface of said platen, a fabric band applied about said ink pad, and means comprising channel-shaped members affixed to said band for attaching the latter to the end portions of said platen, said band retaining said members in position by overlying said members as the latter rock past a dead center position to hold the members hooked over the end portions of said platen.
55. 19. The combination with a curved stencil platen, a fabric ink pad band applied about said platen, and means comprising channel-shaped, hook-like members affixed to the ends of said band for attaching the latter to the edges of said platen, said band retaining said members in position as said members rock past a dead center position over the edges of said platen.

HUGO H. STOELTING.
